COMBINED SADDLE, SUPPORT, BACKREST AND REFLECTOR FOR A BICYCLE

Albert Kamin, 3450 Lake Shore Drive, Chicago, Ill.
60657, and Carl P. Janu, 1640 S. Oak Park Ave.,
Berwyn, Ill. 60402

Filed June 19, 1967, Ser. No. 7,504

Term of patent 14 years

Int. Cl. D12—11, 14

U.S. Cl. D90—1

FIG. 1 is a side elevational view of a combined saddle, support, backrest and reflector for a bicycle showing our new design.

FIG. 2 is a top plan view of the design of FIG. 1.

FIG. 3 is a fragmentary front elevational view of the design of FIG. 1.

FIG. 4 is a fragmentary back elevational view of the design of the invention.

The dominant features of our design reside in the portions shown in full lines.

We claim:

The ornamental design of a combined saddle, support, backrest and reflector for a bicycle, as shown and described.
